SUPPORT FOR SEPARATING STRIPS

Albert C. Fischer, Chicago, Ill., assignor to The
 Philip Carey Manufacturing Company, a cor-
 poration of Ohio

Application February 28, 1927, Serial No. 171,570
 Renewed December 10, 1931

16 Claims. (Cl. 94—8)

My invention relates in general to paving and has particular reference to a convenient and practical means for supporting so-called separating strips as commonly used for separating the 5 divisions of concrete paving.

In referring to separating strips I perhaps should briefly explain just what is meant by the term, so as to avoid any possible confusion. It is a more or less common expedient to divide concrete pavements, or even other concrete structures, into sections so as to avoid possible deterioration of the concrete due to expansion and contraction. These separating strips are sometimes installed every thirty, forty or fifty feet 10 transversely of the road, as an example, and other times a longitudinal strip is used without the transverse strips, or even in combination with the transverse strips.

There are various types of separating strips. 20 Those which are known more often as a separating strip are nothing more than a strip of sheet metal cut to the proper size, and often formed with a so-called tongue on one side and a groove on the opposite side. These metal separating strips quite naturally lack compressible qualities 25 to compensate for expansion of the concrete sections between which they are installed, but they do, however, compensate for contraction of the concrete. Sometimes they are installed with their crowning edges flush with the surface of the concrete, and sometimes they are completely im- 30 bedded in the concrete so that their crowning edges, so to speak, terminate below the surface of the concrete. In this capacity they function primarily to develop a line of weakness for 35 controlling cracks due to contraction of the concrete, so that instead of having the cracks occur irregularly over the surface they are developed along certain lines.

Another form of the so-called separating strips is a preformed strip of compressible material, such as, a mixture of asphalt and fibre. These strips are more frequently referred to as expansion joint strips and are installed for the purpose 40 of compensating for expansion as well as contraction of the concrete.

So far as my support is concerned it is not confined to any of these various types of separating strips, as in reality they are installed in the concrete in more or less the same fashion, i. e. to say, they must be supported on edge perpendicularly with the concrete poured around opposite sides of the strip.

Since the support in this particular instance 45 has been devised primarily for use in combina-

tion with a metal separating strip I have selected this particular form in the accompanying drawing to illustrate the support. In said drawing, Figure 1 is a detailed view in perspective illustrating one form of the invention in combination with a so-called tongue and groove metal separating strip.

Figure 2 is a detailed perspective view of the same form of the invention illustrated in Figure 1 in combination with the metal separating strip 10 without the tongue and groove formation.

Figure 3 is a detailed perspective view of another form of the invention shown in combination with that form of the strip illustrated in Figure 2.

Figure 4 is a detailed perspective view of the base clip.

Figure 5 is a detailed perspective view of the crown clip.

Figure 6 is a detailed perspective view of the 20 head portion of a stake shown in Figures 1 and 2; and

Figure 7 is a detailed perspective view of that 25 form of base clip which is intended to be used when the crowned clip shown in Figure 5 is used.

Referring now to the drawing in detail. A rep- 30 presents a metal separating strip, although as above explained it may be any other form of strip which is intended to be installed in the same way as a metal strip is intended to be. Accord- 35 ing to Figure 1 the separating strip A is made with an intermediate tongue portion B on one side and a groove portion C on its opposite side. As shown, the strip A is intended to be installed on edge, and it is more or less necessary that it be 40 imbedded in the concrete exactly perpendicular, otherwise there would be a tendency of one section of concrete to ride up over a confronting section, especially in instances where the tongue and groove form is not used. Not only is it neces- 45 sary to install the strip perpendicular, but it must be installed in a straight line, otherwise in those forms of separating strips which terminate with their edges flush with the concrete anything but a straight line would make an unsightly instal- lation.

I have devised a very simple, convenient and practical means to install these strips, and ac- 50 cording to Figure 1, which is the preferred form I employ a stake 5, preferably a metal stake, having a head 6, so that it may be hit with a sledge and driven into the ground. The head 6, according to the forms shown in Figures 1, 2 and 6 is made with a strip engaging clip formed by the downwardly depending lip 7, offset from the 55

side 8 of the stake so as to leave an open slot 9 between the lip and the side of the stake.

The slot 9 is made to receive the crowning edge A¹ on the strip A, so that the stake will stand parallel with the strip A with its point 10 adapted to be driven into the ground. Arranged at the bottom of the strip A is a base clip 11, the same having an opening 12 therein for the reception of the stake 5, and an upturned flange 13 which overlies the side of the strip A opposite from that of the stake 5, with the strip confined between the flange 13 and the side 8 of the stake.

In using the support the stake 5 and the base clip 11 may be assembled with the strip A in any fashion most convenient to the one performing the installation. It makes no difference just how the parts are assembled so long as the plate is supported between the head 6 and the base clip 11, with the stake passing thru the opening 12 and into the ground. By driving the stake into the ground the strip A will be securely clamped between the base strip 11 and the head 6. This clamping effect can be readily appreciated when it is considered that the base clip 11 is supported on top of the ground and the stake 5 is free to move thru the opening 12, so that while the stake may be driven into the ground the strip A rests upon the base clip 11 and neither the clip 11 nor the strip A go below the ground surface, consequently the driving of the stake will pull the strip A onto the base clip 11.

The base clip 11 also acts as a support for the strip A and prevents the same from being imbedded in the ground which would ordinarily happen in the absence of the clip 11, as the thickness of the strip is so slight as to present a comparatively sharp edge to the ground surface.

The same effect is established with that form of the support shown in Figure 3, but in this form instead of using the head 6 to engage the crowning edge of the strip the stake 5¹ is made with an ordinary head 6¹ and a crown clip 14 is employed. The construction of the same is best illustrated in Figure 5, and it preferably comprises a clip somewhat on the order of the base clip 11, having an opening 12¹ for the reception of the stake 5¹ and upturned flange 13¹ and a downwardly depending flange 13², with a space between the upturned flange 13¹ and the downwardly depending flange 13² so as to leave an open slot 15 for the reception of the crowning edge of the strip A. The head 6¹ in the stake 5¹ acts as a stop so that the crown clip 14 cannot slip off the stake, and in this way the clip is covered so that it may engage the crowning edge A¹ of the strip, as shown in Figure 3.

60 Due to the fact that the use of a crown clip will offset the strip A from the stake 5¹ it will be necessary, or at least desirable, to slightly change the construction of the base clip for this particular form. Otherwise there will be too much play between the bottom of the strip A and the stake, should a base clip such as 11 be used. To defeat this possibility I make up a base clip 11¹, as shown in Figure 7, which will be practically the same as the base clip 11, except that a slot 15¹ is made by bending the metal of the clip upon itself as at 16, and turning up the end of the clip to make a flange 17. The base of the strip A is received in the slot 15¹ so that the strip is thus supported perpendicularly,

the stake 5¹ being received in an opening 17¹ the same as the opening 12 in the clip 11.

While I have shown and described a strip with only one support it is, of course, understood that as many stakes and sets of clips may be used at spaced intervals along the length of the strip as will be required.

I claim:

1. A support for separating strips, comprising a stake adapted to be driven into the surface 10 upon which the strip is to be supported, and means on the stake adapted to enter into embracing relation with the top and bottom of the separating strip.

2. A support for separating strips, comprising 15 a stake adapted to be driven into the surface upon which the strip is to be supported, and means on the stake adapted to grip the crowning edge of the strip and impart a downward thrust to the strip when the stake is driven into 20 position, and means carried by the stake upon which the separating strip rests to resist said downward thrust of the strip, said last named means adapted to rest upon the surface on which the strip is supported and being slidable relative 25 to the stake.

3. A support for separating strips, comprising means adapted to engage the top and bottom 30 of the strip, and a stake for drawing the same into clamping relation with the top and bottom of the strip when driving the stake into the ground.

4. A support for separating strips, comprising a stake, means at the headed end of the stake to engage the top of the strip, and means at the 35 penetrating end of the stake to engage the bottom of the strip, said last named means being adapted to rest upon the surface of the ground penetrated by the stake to provide a supporting footing 40 for the lower edge of the strip.

5. A support for separating strips, comprising a stake, means at the head of the stake to engage the top of the strip and means on the penetrating end of the stake to engage the bottom of the strip, said last named means having an opening thru 45 which the stake passes, and being adapted to rest upon the surface of the ground penetrated by the stake to provide a supporting footing for the lower edge of the strip.

6. A support for separating strips, comprising 50 a stake, means at the headed end of the stake to engage the top of the strip and means at the penetrating end of the stake to engage the bottom of the strip, said last named means comprising a metal clip having an opening thru which the stake passes, and an upturned flange for embracing the strip and being adapted to rest upon the ground surface to provide a supporting footing 55 for the lower edge of the strip.

7. A support for separating strips, comprising 60 a clip for engaging the crowning edge of a separating strip, and a clip for engaging the edge of the strip base, a stake connecting said clips and adapted to draw the same into clamping engagement with the strip when the stake is driven into 65 the ground upon which the strip is supported.

8. A support for separating strips, comprising a stake having means for engaging the crowning edge of a separating strip, and a supporting member engaging the edge of the strip base, said supporting member having an opening for the reception of the stake and thru which the stake is imbedded in the ground surface.

9. A support for separating strips, comprising a stake, a head on said stake, a downwardly de- 75

- pending offset lip on said head providing a slot on the stake for the reception of the crowning edge of a separating strip, a clip having an opening for the reception of the stake for slidably 5 mounting the clip on the stake, an upwardly projecting offset flange on the clip providing a slot between the stake and the lip for the reception of the edge of the base of the separating strip, said clip adapted to rest upon the surface of the 10 ground penetrated by the stake for supporting the separating strip; whereby the stake on being driven into the ground will clamp the strip between the head and supporting clip substantially as/and for the purpose described.
- 15 10. Separating devices for use in separating adjacent portions of paving, said devices comprising an elongated strip, a stake adapted to be driven into the structure below the strip and a clip movable on the stake adapted to engage an 20 edge of the strip.
11. Separating devices for use in separating adjacent portions of paving, said devices comprising an elongated strip, a stake adapted to be driven into the structure below the strip, and a 25 clip movable on the stake to engage the strip and support same in position.
12. A support for inserting separating strips in paving structures comprising a stake adapted to be driven into a surface upon which a strip is 30 to be supported, said stake having spaced projections extending from a side thereof in position to embrace the edges of the strip, said upper projection having a downwardly depending flange formed at its outer extremity in position to engage the outer surface of a separating strip arranged in supported position in the support.
- 35 13. A support for separating strips in paving comprising a stake having a lower end adapted to

be driven into a surface upon which a separating strip is to be supported, said stake having spaced projections extending from a side thereof in position to engage the upper and lower edges of the strip, said upper projection forming an extension 5 of the top of the stake and having a downwardly depending flange portion formed at its outer extremity and spaced apart from the stake in position to embrace the outer surface of a strip arranged in position in the support. 10

14. A support for inserting separating strips in paving structures comprising a stake having a substantially flat side and adapted to be driven into a surface upon which a strip is to be supported, said stake having spaced projections extending from said flat side in position to engage the opposed edges of a separating strip, said upper projection forming an extension of the top of the stake and having a downwardly depending flange formed at its outer extremity and providing a groove between said flange and said flat surface adapted to receive the crowning edge of a separating strip, said flange being arranged to embrace the outer surface of the strip in order to snugly secure the same against the flat surface 20 of the support. 25

15. Separating devices for use in separating adjacent portions of paving, said devices comprising an elongated strip, a stake adapted to be driven into the structure below the strip, and a 30 strip holding clip removably attached to the stake.

16. A support for inserting separating strips in paving structures comprising a stake adapted to be driven into a surface upon which a strip is to 35 be supported, and a clip engaging the stake on which the strip is adapted to be supported.

ALBERT C. FISCHER.
